[57] **CLAIM**

The ornamental design for a hand-held computer input device, as shown and described.

DESCRIPTION

FIG. 1 is a front left perspective view of an ornamental computer input device showing my new design;

FIG. 2 is a top plan view thereof;

FIG. 3 is a back view thereof; and,

FIG. 4 is a right side view thereof.

The bottom portion not shown is planar and unornamented.
